A. CORTES.CARPET.*No. 20,260.*Patented Nov. 4, 1890.# UNITED STATES PATENT OFFICE.

AUGUSTE CORTES, OF NEW YORK, ASSIGNOR TO THE ALEX. SMITH & SONS CARPET COMPANY, OF YONKERS, NEW YORK.

DESIGN FOR A CARPET.

SPECIFICATION forming part of Design No. 20,260, dated November 4, 1890.

Application filed October 10, 1890. Serial No. 367,642. Term of patent 3½ years.

To all whom it may concern:

Be it known that I, AUGUSTE CORTES, a citizen of the United States, residing at New York city, New York, have invented a new 5 and original Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face 15 view of a carpet showing my new design.

My design consists of a groundwork composed of interlaced scrolls, dispersed among which at irregular intervals are small groups of conventionalized flower forms.

What I claim as new, and desire to secure 20 by Letters Patent, is—

The design for a carpet, consisting of the design substantially as shown.

AUGUSTE CORTES.
